UNITED STATES PATENT OFFICE.

MAURY W. HIBBARD, OF CHICAGO, ILLINOIS.

FLUID-PRESSURE BRAKE.

No. 802,286.

Specification of Letters Patent.

Patented Oct. 17, 1905.

Application filed March 13, 1905. Serial No. 249,779.

To all whom it may concern:

Be it known that I, MAURY W. HIBBARD, a citizen of the United States, residing at Hawthorne avenue and Rees street, Chicago, in the county of Cook and State of Illinois, have invented a new and useful Improvement in Fluid-Pressure Brakes, of which the following is a specification.

My object is to provide certain improvements in the construction of the emergency mechanism of automatic air-brake triple valves; and my present invention is in the nature of an improvement upon the construction shown in application, Serial No. 238,463, filed by me December 27, 1904.

The drawing shows a partly broken vertical central section of my improved valve device.

A is the valve-body, having the train-pipe port *a*, auxiliary-reservoir port *b*, and brake-cylinder port *c*. In the valve-body is a chamber *B*, having a bushing *d*, in which works the emergency-valve piston or movable abutment *C*. The chamber *B* is in open communication with the train-pipe through the port *a*, and in said chamber in the position shown is a small port *e*, from which extends the auxiliary-reservoir feed-passage *f*, containing a non-return valve *g* and terminating at a chamber *h*, in which is a downwardly-seating valve *i*, known as the "feed-valve." Beneath the cap *A'*, which contains the chamber *h*, is a space *D*, from which extends a passage *k* to the exhaust-port *l* of the device. The space *D* is in a ring portion *A²* of the shell or body portion of the valve, formed on its inner side with a spider containing a hub *m*. In the hub *m* is a chamber *n*, from which a passage *p* extends through one of the spider-arms and the shell to the brake-cylinder port or passage *c*. Fitting and sliding upon the hub is a preferably sectional spacer or distance-block *q*, which may be of the exact construction shown in my aforesaid application. Confined between the cap *A'* and ring *A²* is a flexible diaphragm *r*, and confined between the rings *A²* and *A³* is a flexible diaphragm *s*. Confined between the ring *A³* and the top of the main body portion *A* is a flexible diaphragm *t*. The diaphragms *r s* bear against opposite sides of the spacer *q*, whereby they move together under variations of air-pressure. In the chamber *n* is a release-valve *v*. In the upper part of the main body portion is a chamber *w*, communicating through a passage *x* with a chamber *y* in rear of the chamber *B*. In the chamber *w* and fastened to the

diaphragm *t* is a service-valve *z*, working against a seat over a port *2*, which communicates with the brake-cylinder port *c* through a passage *3*. The auxiliary-reservoir port or 60 passage *b* communicates with the chamber *w*, and extending from the said passage to the space above the diaphragm *r* is a reservoir feed-passage *4*. Extending from the feed-passage *f* to the upper side of the diaphragm 65 *t* is a branch passage *5*.

The parts thus far described, embracing the feed, release, and service features of the valve device, are in all main particulars like those shown, described, and claimed in my aforesaid application, and a more detailed description is thought to be unnecessary in the present connection. Their operation, briefly stated, is as follows: Air entering the chamber *B* from the train-pipe passes through the 75 port *e*, passage *f*, and branch passage *5* to the space above the diaphragm *t*, pressing the latter down and seating the service-valve *z*. The air also passes through the center of the ring *A³* to the under side of the double-diaphragm device, pressing the latter upward to first unseat the release-valve *v* and then the feed-valve *i*. This permits pressure to flow from the feed-passage *f* into the space above the diaphragm *r*, thence through the feed-passage *4* to fill the auxiliary reservoir and chambers *w y*. When the latter are charged with pressure approximately equaling that of the train-pipe, the parts will be in balance, the service-valve *z* remaining closed under 80 the relative suction action at the port *2*. A service reduction of pressure in the train-pipe causes the same reduction to be felt between the diaphragms *s t*, permitting the then superior reservoir-pressure bearing upon the 85 diaphragm *r* to lower the double-diaphragm device, which causes the feed and release valves to close, and the reservoir-pressure acting against the under surface of the diaphragm *t* raises the latter and unseats the 90 service-valve, whereby pressure will flow to the brake-cylinder to apply brakes. When the auxiliary-reservoir pressure drops nearly to the then reduced train-pipe pressure, the service-valve *z* will close under the suction at 95 the port *2*. The same operations will take place under further slight reductions of train-pipe pressure for graduations. When train-pipe pressure is raised to release brakes, the pressure enters between the diaphragms *s t* 100 to press the service-valve firmly to its seat, open the release-valve *v*, and then in the fur-

ther rise of the double-diaphragm device open the feed-valve *i*. Thus exhaust of pressure from the brake-cylinder commences before the feed-valve *i* is opened to replenish the 5 auxiliary reservoir.

Extending between the chambers *B* *y* is a large central opening *y'*, surrounded by a bushing 6, forming a seat for a valve-ring 7 on the rear side of the emergency-piston *C*. 10 In the bushing *d* of the chamber *B*, in the position shown, are ports 8, leading to an emergency-passage 9, terminating in an enlargement or chamber 10. The chamber 10 communicates with the brake-cylinder passage *c* through a port surrounded by a bushing 11, forming a valve-seat. Extending between the chambers *y* 10 is a guide-opening *y'*, surrounded by a bushing 12, presenting a valve-seat in the chamber *y*. The stem 13 of 15 the piston *C* extends through the opening *y'* and is provided toward its end with a screw-thread 14 and in its end with a recess or chamber 15. Screwed upon the end of the stem 13 is a cup 16, having a central guide-opening 17. Confined between the inner end of the cup 16 and the rear face of the piston *C* is a cylindrical spacer or ring 18, carrying a seating-ring 19, bearing against the end of the cup and pressing at its forward end against 20 the ring 7 to hold the latter in place. The rings 7 19 are preferably of rubber or other suitable material, which will conform to the seats 6 12 and form air-tight joints.

E is the emergency-valve, having a seating-ring 20 fitting the seat 11. The valve is upon a sliding extension 21 of the piston-stem 13. This extension comprises a shank which carries the valve *E* and an enlarged head portion 22 in the chamber 15 and moving or sliding 25 therein between the stops formed by the base of said chamber and the flanged portion of the cup 16, surrounding the guide-opening 17. The rear end face 23 of the cup 16 may be concave, as shown, and the rear face 24 of the valve *E* about the stem 21 is convex. When the parts are in normal position, as shown, a space 25 exists between the cup 16 and valve *E*, and the head or shoulder 22 is separated a short distance from both the stops formed by 30 the base of the chamber 15 and the inward-projecting end portion of the cup 16.

During the operations of the valve device for service application of brakes and while all the parts are in running position the piston 35 *C*, emergency-valve *E*, and attendant parts will occupy the relative positions shown, the piston being held with desired firmness against the seats 6 12 by the emergency-spring 26 shown. To prevent this spring from buckling, I provide therein a loose tube 27. At all 40 times when the train-pipe pressure exceeds the pressure in the brake-cylinder the valve *E* will be held to its seat by the force of train-pipe pressure exerted against the rear side of 45 said valve in the space 25. The piston *C* fits

loosely the bushing *d*, so that the rear side of the piston around the seat 6 is in restricted communication with the train-pipe air. Reservoir-air pressure is normally exerted against the rear side of the piston over the annular 50 space bounded at its inner annular edge by the seating projection of the bushing 12 and at its outer annular edge by the seating projection of the bushing 6. Thus as the area against which reservoir-pressure exerts itself 55 against the piston is comparatively small a comparatively weak and sensitive emergency-spring 26 may be provided. This area is sufficient to cause the reservoir-pressure under emergency reduction of train-pipe pressure to overcome the resistance of the spring 26 and move the piston *C* from the seat 6 until the shoulder at 17 engages the emergency-valve stem. This unseating of the piston permits the reservoir-air to bear against 60 the entire area of the rear side of the piston, thereby overcoming the resistance of the emergency-valve against unseating and forcing the piston to the position where its annular seating edge 28 bears against the gasket or 65 seat 29. When the emergency-valve is thus initially opened, a rush of pressure will take place from the train-pipe through the ports 8 and passage 9 to the brake-cylinder to effect 70 serial or quick action emergency application 75 of brakes in the manner well understood. Seating of the piston against the seat 29 shuts off communication between the feed-passage *e* and train-pipe and also between the ports 8 and train-pipe, so that during emergency 80 application of brakes there can be no retrogression of pressure from the brake-cylinder to the train-pipe. When train-pipe pressure is raised following emergency action, it will, as soon as it, supplemented by the 85 spring 26, is capable of overcoming the reservoir and brake-cylinder pressures, move the piston in the direction of seating the emergency-valve. As the piston in its backward 90 movement opens the ports 8 a sudden retrogression of pressure will take place from the brake-cylinder and reservoir to the train-pipe, thereby producing, as explained in my aforesaid application, serial release following 95 emergency action. When the auxiliary reservoir and brake-cylinder are emptied of pressure, there is of course no pressure behind the emergency-piston *C*. When a car 100 with empty reservoir and brake-cylinder is coupled to a train, usually the full force of 105 train-pipe pressure is suddenly let into the triple valve and must pass through the small feed-port and feed-valve to charge the auxiliary reservoir and the chamber behind the 110 emergency-piston. In the meantime pressure 115 passes more quickly into the emergency-passage 9, and where, as in my former construction referred to, this pressure can exert itself 120 against the emergency-valve in the direction of unseating it, it is apt to open the valve 125 130

and escape to a material extent through the emergency-port and thence through the exhaust-port. In my present construction this cannot take place, because the train - pipe 5 pressure exerts itself against the emergency-valve in the space 25 and chamber 15 to press the same to its seat and maintain the emergency-port closed.

I have shown my improvements in the form 10 in which I now prefer to provide them; but it will be obvious that changes may be made in the matter of details of construction without departing from the spirit of my invention as set forth in the appended claims.

15 What I claim as new, and desire to secure by Letters Patent, is—

1. In a device for actuating air-brakes, the combination with feed, release and service mechanisms, of a valve-body having an emergency-port and passage extending from the train-pipe connection to said port, an emergency-valve-operating movable abutment, and a valve for said port movably connected with 20 said abutment and independently exposed on one side to seating pressure from said passage.

2. In a device for actuating air-brakes, a valve-body having an emergency - port and passage extending from the train-pipe connection to said port, a movable abutment exposed on one side to train-pipe pressure only 25

and exposed on its opposite side to reservoir and restricted train-pipe pressures, and a valve for said port movably connected with said abutment and independently exposed on one side to seating pressure from said passage. 35

3. In a device for actuating air-brakes, the combination with a triple-valve body, of quick-action emergency-valve mechanism physically and operatively independent of the service-valve mechanism and comprising a movable 40 abutment exposed on one side to train-pipe pressure only and on its opposite side to auxiliary-reservoir and restricted train-pipe pressures, and an emergency-valve loosely connected with said abutment and independently 45 exposed at one side to seating pressure from the train-pipe.

4. In a triple valve for air-brakes, emergency-valve-operating mechanism comprising a piston, a piston-stem, a cup on the end of 50 the stem, a spacer around the stem interposed between the piston and cup, and seating-rings at opposite ends of the spacer, in combination with an emergency-valve slidably mounted in the cup.
